UNITED STATES PATENT OFFICE.

MYRON H. RICHARDSON, OF WICHITA, KANSAS.

ADVERTISING DEVICE.

SPECIFICATION forming part of Letters Patent No. 553,598, dated January 28, 1896.

Application filed April 15, 1895. Serial No. 545,803. (No model.)

To all whom it may concern:

Be it known that I, MYRON H. RICHARDSON, a citizen of the United States of America, residing at Wichita, in the county of Sedgwick and State of Kansas, have invented 5 certain new and useful Improvements in Advertising Devices, of which the following is a specification, reference being had therein to the accompanying drawings, and the figures 10 of reference thereon, forming a part of this specification; in which—

Figure 1 represents a portion of a door, looking from the inside, showing my advertising device attached thereto. Fig. 2 is a 15 detail of the spring and block, showing the position of the spring when the door is closed and the advertising device is hanging in a perpendicular position. Fig. 3 is a detail of the same, showing the position when the door 20 is open. Fig. 4 is an end view of my advertising device with the spring attached. Fig. 5 is a sectional view of the block and spring through line 1 of Fig. 2. Fig. 6 is a front view of my advertising device, and Fig. 7 is 25 a back view of the same.

This invention relates to certain improvements in advertising devices; and it consists of a frame adapted to hold a card with the desired advertisement on it, and the means 30 of securing said frame to the inside of the door in one position when the door is closed and in another when said door is open.

Referring to the drawings, 1 represents a door-casing.

35 2 is a door-stile, and 3 represents a glass in the door.

4 is a portion of the frame of the advertising device.

5 represents a chain, one end of which is 40 attached to the door-casing at 7, and the other end is attached to the frame 4 with the screw 6. The frame 4 is pivotally held to the block 9 by the screw 8.

10 represents screw or nail holes for securing the block 9 to the door-stile through the 45 medium of screws or nails.

12 represents the portion of the block 9 around which the spring 11 is coiled.

14 is a loop on the end of one of the arms 50 of the spring, which attaches to the frame 4 with the pin 19. 15 represents the loop on the end of the other arm of said spring for

securing said spring to the block 9 in the recess 18 by the screw 16. 17 represents a recess in said block 9 to allow the arm 14 to 55 freely swing around to carry the frame 4 from a perpendicular to a horizontal position.

20 represents a portion of the frame 4 adapted to receive an advertising-card 21.

Other kinds of springs may be used in place 60 of the coil-spring used in connection with the block and frame.

In placing this advertising device on the door the block is secured to the door-stile with screws or nails. The chain 5 is first attached to the frame 4 at 6. Then the opposite end is attached to the door-casing, so as to hold the frame 4 in a perpendicular position when the door is closed. The block 9 is placed so the spring 11 will be just stiff enough 65 to swing the frame 4 to a horizontal position when the door is opened. If the spring should be too weak to bring the frame 4 to the desired position, the block is twisted around to the left and secured to the door. When the door 70 is closed the advertising device stands in the position shown by the solid lines in Fig. 1, and as the door is swung open it slackens the chain 5, which allows the spring 11 to swing the frame 4 up to the position shown by the 75 dotted lines in Fig. 1, which will attract the attention of the person opening the door, when the advertisement on the card will be seen.

The cards can be changed at will by slipping one out of the portion 20 of the frame 4 80 and putting another one in its place.

Having thus described my invention, what I claim as new and useful, and desire to secure by Letters Patent, is as follows:

1. In the herein described advertising device 90 consisting of a frame for removably holding an advertising card, said frame pivotally secured to the door stile, a chain with one end secured to said frame, the other end secured to the door casing, a block having the 95 post 12, and the depressed portions 17 and 18, a coil spring with one end secured in said depressed portion 18, the other end of said spring adapted to swing in said depressed portion 17 to govern the distance of the swing 100 of the frame.

2. In the herein described advertising device in combination with the door and door casing, of a block provided with the depressed

portions 17 and 18 adapted to hold the coil
spring, with one end of said spring secured
in one of said depressed portions, the other
end adapted to swing in the other of said de-
5 pressed portions, and secured to a frame, said
frame adapted to removably hold an adver-
tising card, and a chain with one end secured

to said door casing and the other secured to
the said frame.

MYRON H. RICHARDSON.
